R. BAER.

PERMUTATION LOCK.

APPLICATION FILED JUNE 2, 1921.

1,391,359.

Patented Sept. 20, 1921.

Fig. 1.

UNITED STATES PATENT OFFICE.

RICHARD BAER, OF NEW YORK, N. Y.

PERMUTATION-LOCK.

1,391,359.

Specification of Letters Patent. Patented Sept. 20, 1921.

Original application filed May 19, 1920, Serial No. 382,645. Divided and this application filed June 2, 1921. Serial No. 474,359.

To all whom it may concern:

Be it known that I, RICHARD BAER, a citizen of Czechoslovakia, and resident of the borough of Manhattan, in the city, county, and State of New York, have invented certain new and useful Improvements in Permutation-Locks, of which the following is a description.

The present invention relates to improvements in permutation locks, and has for its object to provide a lock adapted for use upon ordinary house doors or the like, and which may be operated with facility by one knowing the combination of the same.

This application constitutes a division of co-pending application Serial No. 382,645, which was filed May 19, 1920, and entitled Permutation locks.

A further object is to provide a lock which may be readily operated from one side of the door without the manipulation of the permutation means, and which will automatically lock itself when the door is closed.

Other objects are to provide a lock which will not readily get out of order, which will be simple and economical in construction, and practicable for house door use. It is further proposed to enable the changing of the combination whenever desired.

With these and other objects in view, embodiments of my invention are shown in the accompanying drawings, and these embodiments will be hereinafter more fully described with reference thereto, and the invention will be finally pointed out in the claims.

In the accompanying drawings:

Figure 1 is a front elevation of the adjacent portions of a door and a door jamb provided with a lock according to one embodiment of my invention.

Fig. 2 is a horizontal section view along the line 2—2 of Fig. 1.

Fig. 3 is a detail perspective view of the bolt and locking members.

Fig. 4 is a front view of the locking member in unlocked position, and

Fig. 5 is a similar view showing the same in locked position.

Similar reference characters indicate cor-

responding parts throughout the several figures of the drawings.

Referring to the drawings, the embodiment of my invention shown therein comprises a casing 105, having a series of gears 106, 107, 108 and 109 mounted therein. These gears are adjustably fixed by set screws 74 upon the inner ends respectively of sleeves 28, 31, 34 and 37 which are concentrically arranged and rotatable relative to each other and to a supporting shaft 21 which is mounted transversely in the casing 105 and held therein by a nut 26.

The said gears mesh respectively with a series of vertically movable block members 110, 111, 112, and 113, having toothed rear surfaces and mounted upon vertically disposed guide rods 114, 115, 116 and 117, held at their ends in the upper and lower sides of the casing. The contacting surfaces of the several block members are recessed and fitted within each other, the members 110 and 113 being recessed at their rearward portions as at 118 and 119, and the members 111 and 112 at their forward portions, as at 120 and 121, so that the front faces of the members 110 and 113 are relatively wide and the front faces of the members 111, and 112 disposed therebetween, are relatively narrow.

A circular recess or socket 122 is provided centrally of the several block members, being common to all of them, and extending entirely across the members 111, and 112, and partially into members 110 and 113. Relatively vertical shifting movement of the said members is adapted to so disarrange the several portions of the socket as to produce a non-circular socket. By manipulation of the permutation means to predetermined positions, the block members may be brought into such position, as indicated in Figs. 3 and 4, and in which the socket is circular.

Within the casing, and forwardly of the block members there is provided a bolt member 123, guided between parallel plates 124 and 125, and provided at its forward face with a nose portion 126, adapted to be projected and retracted through an opening 127 in the casing, and provided at its rear face 100

with a circular plug portion 128, disposed in line with the socket 122 in the circular position thereof, and adapted to be engaged therein, the nose 126 being retracted when 5 so engaged, and being prevented from entering the socket in the non-circular position thereof, so that the bolt is locked in projected position.

10 A handle shaft 129 is provided above the guide plate 124, being journaled at its inner end in the casing, and at its outer end in a bushing 130, a handle 131 being provided thereon. Interiorly of the casing the shaft is provided with an arm 132, extending 15 downwardly through an opening 133 in the plate 124, and engaging between pins 134 and 135, provided in the side of the bolt member, the bolt member adapted to be projected and retracted by operation of the 20 handle.

25 Helical springs 136 are respectively mounted on rods 114, 115, 116 and 117 alternately above and below the block members, and are adapted when the plug portion 128 of the bolt is removed from the socket, to automatically move the block members, so that the circular arrangement of the 30 socket is destroyed.

35 The jamb is recessed, and a strike plate 30 may be fastened, as at 137, to receive the bolt in the projected position thereof, and a keeper mounted in relation thereto, comprising a casing 138, in which is slidably mounted a bolt 139, adapted to be projected 40 and retracted through an opening 140 in the front face of the casing, a shaft 141 projecting from the rear side of the bolt through a hole 140 in the casing, a spring 142, provided thereon, adapted to normally urge the bolt toward projected position, and in which 45 position the door is locked when the nose 126 of the bolt 139 is projected. The projecting end of the bolt 139 is beveled, as at 144, so that when closing the door with the bolt 50 126 projected, the beveled surface will be engaged, causing the bolt 139 to be pressed in until the bolt 126 passes beneath the same, whereupon it will be projected by means of the spring, into locking position.

55 The door may be opened from the inside, when the bolt 126 is projected, by manual retraction of the bolt 139, a handle 145, extending through a slot 146, being secured to the bolt for this purpose.

60 I have illustrated and described preferred and satisfactory embodiments of my invention, but it is obvious that changes may be made therein, within the spirit and scope thereof, as defined in the appended claims.

65 I claim:

1. In a lock, a casing, a shaft in said casing, a plurality of superimposed relatively rotatable sleeves upon said shaft, a plurality of gears respectively mounted upon the inner ends of said sleeves, the outer ends of

said sleeves being exposed to permit of independent operation thereof to turn said gears, a plurality of relatively movable members having teeth engaging said respective gears, and having bolt engaging portions, 70 a bolt in said casing adapted to be retracted and projected, and having means to engage said bolt engaging portions in retracted position, and in a predetermined position of said sleeves in which said portions are in 75 alinement with said means on said bolt.

2. In a lock, a casing, a shaft in said casing, a plurality of superimposed relatively rotatable sleeves, upon said shaft, a plurality of gears respectively mounted upon 80 the inner ends of said sleeves, the outer ends of said sleeves being exposed to permit of independent operation thereof to turn said gears, a plurality of relatively movable members having teeth engaging said respective 85 gears, and having bolt engaging portions, a bolt in said casing adapted to be retracted and projected, and having means to engage said bolt engaging portions in retracted position, and in a predetermined position of 90 said sleeves in which said portions are in alinement with said means on said bolt, and spring means adapted to move said members to disaline said bolt engaging portions when said means on said bolt is removed therefrom.

3. In a lock, a casing, a shaft in said casing, a plurality of superimposed relatively rotatable sleeves upon said shaft, a plurality of gears respectively mounted upon the 100 inner ends of said sleeves, the outer ends of said sleeves being exposed to permit of independent operation thereof to turn said gears, a plurality of relatively movable members having teeth engaging said respective 105 gears, and having bolt engaging portions, a bolt in said casing adapted to be retracted and projected, and having means to engage said bolt engaging portions in retracted position, and in a predetermined position of 110 said sleeves in which said portions are in alinement with said means on said bolt, and a keeper having a bolt adapted to be projected and retracted, and adapted to be lockingly engaged with said first-mentioned bolt 115 in the projected position thereof.

4. In a lock, a casing, a shaft in said casing, a plurality of superimposed relatively rotatable sleeves upon said shaft, a plurality of gears respectively mounted upon the 120 inner end of said sleeves, the outer ends of said sleeves being exposed to permit of independent operation thereof to turn said gears, a plurality of relatively movable members having teeth engaging said respective 125 gears, and having bolt engaging portions, a bolt in said casing adapted to be retracted and projected, and having means to engage said bolt engaging portions in retracted position, and in a predetermined position of 130

said sleeves in which said portions are in alinement with said means on said bolt, a keeper having a spring pressed bolt provided with a beveled surface adapted to be pressed to retracted position upon closing engagement of said first-mentioned bolt therewith, and adapted to be projected into locking re-

lation with said first-mentioned bolt, as said first-mentioned bolt is moved past said spring pressed bolt. ¹⁰

In testimony that I claim the foregoing as my invention, I have signed my name.

RICHARD BAER.
